UNITED STATES PATENT OFFICE.

WILLIAM F. GROENE, OF CINCINNATI, OHIO, ASSIGNOR TO THE R. K. LE BLOND
MACHINE TOOL COMPANY, OF CINCINNATI, OHIO, A CORPORATION OF OHIO.

LATHE.

1,358,728.

Specification of Letters Patent. Patented Nov. 16, 1920.

Application filed August 6, 1917. Serial No. 184,731.

To all whom it may concern:

Be it known that I, WILLIAM F. GROENE, a citizen of the United States, residing at Cincinnati, county of Hamilton, and State 5 of Ohio, have invented an Improvement in Lathes, of which the following description, in connection with the accompanying drawings, is a specification, like characters on the drawings representing like parts.

10 The invention hereinafter described relates to lathes, and among other objects, aims to provide a mechanism for forming parts of shrapnel shells and other work.

In the manufacture of shells, it is customary to turn a circumferential groove or seat in the shell to receive the copper ring which is sufficiently large to slip over the end of the shell and is then compressed tightly into the groove. The ring must be 15 securely held in the groove since it is used to snip into the rifling in the barrel of the gun and thereby impart the rotary movement to the shell in its transit through the barrel.

20 To hold the ring in the groove, it is desirable to form the latter with undercut edges so that it is dovetail in transverse section. To prevent circumferential creeping of the ring in the groove, it is desirable 25 to provide the latter with a rib or ribs having undulations extending circumferentially of the groove.

The means heretofore used for making these grooves is cumbersome and difficult 30 to operate quickly and with the necessary accuracy of performance. However, by the present invention, a simple mechanism is provided which will easily, quickly, and accurately form these grooves and do other 35 work, as required.

The character of the invention may best be understood by reference to the following description of one good form thereof shown in the accompanying drawings, 40 wherein:

Figure 1 is a view partially in plan and partially in horizontal section of the mechanism shown herein as embodying the invention;

45 Fig. 2 on an enlarged scale is a vertical section through a portion of one of the tool rests and a part of the carriage, showing cam means for reciprocating one of the tools axially of the shell;

50 Fig. 3 on an enlarged scale, is a vertical

transverse section taken on the line 3—3 of Fig. 1;

Fig. 4 is a perspective view of the mechanism for feeding the undercutting tools toward and from the shell; 60

Fig. 5 is a perspective view of the undercutting tools, their rests and a part of the device for feeding said tools;

Fig. 6 is a perspective view of the groove and rib forming tool, its rest, a portion of 65 its support, and the shaft for rotating the cam means for reciprocating the tool axially of the shell;

Fig. 7 on an enlarged scale, is a plan of a portion of the shell showing the relation of 70 the groove and rib forming tool and the undercutting tools therewith in forming the band seat; and

Fig. 8 is a development of the cam for feeding the groove and rib-forming tool 75 toward and from the shell.

Referring to the drawings: The lathe shown therein as embodying the invention comprises a carriage 1, Fig. 1, mounted on the bed of the lathe in the usual manner. 3 80 designates the live spindle on a shaft journaled in a bearing in the head 5. The head spindle 7 is mounted in the head 9 and is clamped thereto by a screw 11 projecting through the split portions of said head. 85 The machine is adapted to perform various kinds of work, but in the present instance of the invention, it is shown set up for turning the band seat groove in a shrapnel shell 13 which is mounted between the live and 90 dead spindles. To contribute to the support of the shell, it may be mounted in a chuck 15 having a neck 17 at one end thereof threaded on the spindle shaft. The main body of the chuck may be somewhat larger 95 than the diameter of the shell so as to loosely receive the latter. At the opposite end of the chuck is a collar 19 closely fitting the shell and secured to the body of the chuck by screw bolts 21. The base of the shell 100 may be positioned on the dead spindle by a plug 23 fitting the internal bore of the shell. To rotate the shell with the live spindle and chuck, the latter may have an internal lug 105 positively engaging a dog 27 on a plug 29 threaded into the nose of the shell.

To turn the band seat in the shell, a suitable tool is provided. In the present instance of the invention, a tool 31, Figs. 1, 6 and 7, is employed having a series of teeth 110

33 with grooves 35 between them for forming a series of circumferential ribs 37 on the shell. These teeth project from the dove-tail shank 39 of the tool mounted in a similarly-shaped groove in a block 41, Fig. 6, mounted on a tool rest 47. This block may be adjusted relatively to the tool rest and held in different positions with respect to the work by screws 49. The shank of the 10 tool is adjustably held in the block by means of a plate 50 secured to the block by screws 51. The tool may be elevated to take up wear by means of an adjusting screw 52, Figs. 3 and 6, threaded in the support for the tool rest and adapted to engage the lower end of the tool.

The groove and rib-forming tool may be automatically fed toward the shell to cut a groove of the exact depth required therein, 20 and then it may be automatically retreated therefrom. In the present instance of the invention, the tool is fed gradually in toward the work to perform its cut, then pauses while the tool is finishing the bottom 25 of the groove, and then rapidly withdraws from the groove.

To accomplish this, the tool rest support 53 has a dove-tail groove 55 receiving a similarly-shaped projection 56 extending 30 from the front to the rear of the carriage. This permits the tool to slide toward and from the shell or other piece of work transversely to its axis.

To reciprocate the support, a plate 53^a, 35 Figs. 1 and 3, is mounted on the front end thereof and adjustably connected thereto by a screw 57 entered through an elongated slot 59 in said plate and threaded in said support. Screws 61 may be threaded into a 40 depending lip 63 on said plate and react against the front end of said support to give the plate its desired nicety of adjustment. Tracks 65 project up from the support at the sides of the plate to guide it 45 properly in its adjustment.

A follower 67 in the form of a stud threaded in said plate projects downwardly beneath the latter and carries a roller 69 projecting into the circumferential groove of a cam 71 fast on a shaft 73 projecting transversely of the carriage and journaled in suitable bearings thereon. This shaft may be automatically driven by a pinion 75 meshing with a gear 77 mounted in the 50 apron of the carriage and driven by the usual driving mechanism therein. The shaft 73 may be provided with ball bearings 79 to reduce the friction from the thrust in the direction of the axis of said shaft. A 55 handwheel 81 fast on the front end of said shaft permits manual rotation thereof when required.

When the shaft 73 is rotated, the cam 71 will be rotated and acting on the follower 65 69, will feed the tool rest support in and out

along the dove-tail guide connections between the support and the carriage.

Referring to the development of the cam shown in Fig. 8: it will be noted that its groove comprises a portion *a—a* for gradually feeding the groove and rib-forming tool toward the shell, a portion *a—b* for causing the tool to dwell or pause at the limit of its infeed to finish the bottom of the groove, and a portion *a—c* of relatively sharp incline for quickly withdrawing the tool from the shell after the completion of the groove.

Next will be described the means for reciprocating the tool as it is fed inwardly in order to produce a rib or ribs in the groove having a series of undulations extending circumferentially of the groove. To accomplish this, the tool rest has a tongue and groove connection 83, Figs. 3 and 6, with the support, thereby permitting the tool rest to slide axially of the shell. A stud 85, Fig. 2, is threaded into the tool rest and has a roller 87 projecting into a circumferential groove 89 of a cam fast on a shaft 91 journaled in bearings in the tool rest support. To limit movement of said shaft axially thereof, it may have a reduced end 93 with a sleeve 95 thereon having at one end thereof a collar 97 engaging a shoulder in 95 a recess in said support accommodating the cam. A ball bearing 99 confined between one end of said cam and said collar will cooperate with the latter to limit movement of the shaft toward the right of Fig. 2, and a ball bearing 101 confined between the end of a counterbore in said support and a collar 103 on said shaft will limit its movement in the opposite direction.

To rotate said shaft, it is connected by a knuckle 104 to one end of a telescoping shaft 105, the opposite end of which is connected by a knuckle joint 107 with a stud shaft 109 journaled in a bearing bracket 111 mounted on the front of the head stock. A pinion 113 fast on said stud is driven by a large gear 115 mounted on the neck of the chuck and secured to the latter by screw bolts 117.

By the construction just described, the large gear will rotate with the live spindle, 115 thereby rotating the pinion 113, the telescoping shaft, the cam shaft, and the cam, thereby causing the tool rest to slide on its support axially of the shell. The flexible telescoping shaft will allow the tool rest to 120 be reciprocated in a direction perpendicular to the axis of the shell and also in a direction parallel with said axis.

Preferably, the ribs in the groove should receive a number of undulations in the 125 course of one rotation of the shell. This number may be determined by a ratio between the large gear 115 and the pinion 113 equal to the number of undulations to be produced.

Having described the tool for forming the groove and the undulatory ribs therein, next will be described the means for undercutting the edges of the groove to produce a band seat which is dove-tailed in cross section. To accomplish this, a pair of tools 119, Figs. 1, 5 and 7, may be provided, clamped by plates 121 and screws 123 on the tool rests 125 having the dove-tail tongues 127 projecting into similarly-shaped grooves 127^a, Fig. 4, in a support 128 mounted on an extension of the tongue on the carriage on which the rib and groove tool support slides. The support 125 may be adjustably secured to the carriage by a screw 128^a, Fig. 1, entered through an elongated slot in said support and threaded into said carriage. The dove-tail grooves diverge from one another as will be noted in Fig. 4, and the tool rests are adapted to slide along these grooves toward and from the shell. As a consequence, as the tools are advanced toward the shell, they will gradually spread outward and increase the width of the groove until the maximum width is produced at the bottom of the groove.

To slide the tool rests in their grooves, they are provided with arms 131, Fig. 5, secured to cross-heads 133 adapted to slide in a channel guide 135 extending transversely of the dove-tail grooves, mounted on a slide 137 adapted to reciprocate in a guideway in the support 128 at the rear of said tool rests.

A plate 139 is mounted in a groove 141 on said slide and is adjustably secured thereto by a screw 143 entered through an elongated slot 145 in said plate and threaded into said slide. A follower in the form of a pin 147 projects downward through said plate and has a roller 149 working in a circumferential groove of a cam 151 mounted fast on the shaft 73 referred to. Screws 153 are threaded into a lip 155 depending from the plate 139 and are adapted to bear against the end of the slide 141 to facilitate adjustment of the plate with respect to said slide with the nicety of adjustment desired.

By the construction just described, the undercutting tools will be reciprocated in divergent paths toward and from the work. The cam for reciprocating these tools may be substantially of the same general character as the cam for reciprocating the groove and rib forming tool toward and from the work, and similarly said cam may have a portion for feeding the tool gradually into the groove to the required depth, a portion for causing the tools to dwell at this depth to finish the bottom of the edges of the groove, and a portion for causing the quick withdrawal of the tools from the work.

Since the cams for the opposed tools are

mounted on the same shaft, they may be conveniently arranged to feed in toward the work simultaneously, dwell simultaneously, and withdraw simultaneously, although this simultaneous action is not indispensable.

Since the groove and rib forming tool is reciprocated axially of the work, it produces not only an undulatory rib, but also an undulatory groove, and if the undercutting tools were not employed, the finished groove would be undulatory. The undercutting tools not only serve to undercut the edges of the groove, but also serve to produce the straight edges of the finished groove. Therefore, it will be apparent that they might be used merely to straighten the edges without undercutting, if desired.

In operation the shell or other work to be treated is mounted between the live and dead spindles, and secured in its chuck so as to be driven from the live spindle. Then the groove and rib forming tool and the undercutting tools are set the required distances from their actuating cams to cut a groove of the required depth. Then the machine is driven, thereby causing the cams on the cross shaft to gradually feed the tools to the required depth. In the course of this feed the rib and groove forming tool will be moved axially of the shell by the cam driven by the flexible extensible shaft from the spindle shaft. When the tools have been fed in the requisite depth, the cams on the cross shaft will cause the tools to dwell to finish the bottom of the groove throughout the circumference thereof. Then the cams on the cross shaft will rapidly withdraw the tools from the work. The band seat in the shell is now completed and the shell may therefore be removed from the lathe and another substituted therefor, whereupon the operations described may be repeated.

The mechanism described may be very easily and quickly controlled, and it will reliably, accurately and quickly form band seats for shells and do other work as desired.

It will be understood that the invention is not limited to the specific embodiment shown herein, but that extensive deviations may be made therefrom, without departing from the spirit and scope of the appended claims.

Claims:

1. In a lathe, the combination of the machine bed, means for supporting and rotating the work, a carriage movable longitudinally along said bed, tool rests movably mounted on said carriage, a shaft mounted on and extending continuously from front to rear of said carriage, cams on said shaft operatively connected with said tool rests for moving the same toward and from the work,

and a cam for reciprocating one of said tool rests transversely to the direction of movement of the others.

2. In a lathe, the combination of means for supporting and rotating the work, a carriage, cross slides on the carriage movable toward and from the work, a slide mounted on and movable transversely to the direction of movement of one of said cross slides, cams mounted on said carriage for moving said cross slides toward and from the work, a cam on one of said cross slides for moving said transverse slide, and means for rotating said cams to impart reciprocatory movements to said slides.

3. In a lathe, the combination of means for rotating the work, a tool for producing a wavy groove in the work, a rest supporting said tool, a cross slide supporting said rest, a pair of tools for undercutting the edges of said groove, a pair of slides supporting said undercutting tools and movable in divergent paths, rotary cam means for moving said cross slides toward and from the work, and rotary cam means mounted on one of said cross slides for moving the tool rest for the waving tool transversely to the path of movement of said cross slides.

4. In a machine of the class described, the combination of the bed frame, a carriage mounted for movement longitudinally on the bed frame, a single transverse shaft mounted on and movable with the carriage, a tool rest at the front and a tool rest at the rear of the carriage, cams on the transverse shaft, one at the front and one at the rear of the carriage and movable therewith, connections between the respective cams and the tool rests for automatically moving the tool rests toward the work and after a dwell to withdraw the tool rests from the work, and means for reciprocating one of the tool rests in a direction substantially parallel to the axis of the work to produce a waving cut in the work.

5. In a machine of the class described, the combination of a bed frame, a carriage, tool rests mounted on the carriage, one at the front and the other at the rear thereof, a turning tool mounted on one of the tool rests, an undercutting tool mounted on the other of the tool rests, a single shaft mounted on the carriage and extending from front to rear thereof, a cam at the front and one at the rear of the carriage connected to said single shaft, and means between the tools and cams for causing one tool to move at substantially right angles to the axis of the work and the other tool to move in an oblique direction.

6. In a lathe, the combination with means for supporting and rotating the work, a carriage for supporting the tools to act upon the work of a tool for forming a circumferential groove in the work, a tool for un-

dercutting an edge of said groove, a single shaft extending from front to rear of the carriage, and cams on said shaft for automatically feeding the tools slowly toward the work during the cutting action and then rapidly withdrawing the tools.

7. In a lathe, the combination with means for supporting and rotating the work, of a tool for forming a circumferential groove in the work, means for feeding said tool toward said work to cut a predetermined depth therein, and acting to cause said tool to dwell to finish the bottom of the groove, and then withdraw the tool from the work.

8. In a lathe, the combination with means for supporting and rotating the work, of a tool for forming a circumferential groove in the work, a tool for cutting the edges of the groove, and means for causing said tools to be moved simultaneously toward the work and when the groove has been cut, to dwell and finish the groove and then to be withdrawn from the work.

9. In a machine of the class described, the combination of the bed frame, means for supporting and rotating the work, a carriage, a support on the carriage at one side of the work, a tool rest on said support, a cam mounted on said support for moving the tool rest axially of the work, a second support on the carriage at the opposite side of the work, a tool rest on said support, a shaft mounted on the carriage, cams on said shaft and connections between the cams and supports for moving both supports toward and from the work while one of them is being moved axially of the work.

10. In a machine of the class described, the combination of the bed frame, means for supporting and rotating the work, a carriage, a support on the carriage at one side of the work, a tool rest on said support, a cam mounted on said support for moving the tool rest axially of the work, a second support on the carriage at the opposite side of the work, a tool rest on said support, a single shaft mounted on the carriage and extending from front to rear thereof, two cams, one fixed to the shaft at the front and the other fixed to the shaft at the rear of the carriage, and means for automatically rotating all three cams specified to cause the tool rests to move simultaneously toward and from the work as one of them is moved axially of the work.

11. In a lathe, the combination with means for supporting and rotating the work, of a pair of tools movable in divergent paths toward and from the work, a guideway extending transversely to said paths, cross heads connected to said tools reciprocable in said guideway, and means for reciprocating said guideway to slide said tools in said divergent paths.

12. In a lathe, the combination with

means for supporting and rotating the work, of tools acting in divergent paths relatively to the work, rests supporting said tools, a cam, a follower coöperating with 5 said cam, means connected to said rests, and means adjustably securing the same to said rests to vary the distance of said tools from said cam means.

13. In a lathe, the combination with 10 means for supporting and rotating the work, of tools for forming edges of a groove in the work, rests for said tools, a support for said rests, divergent guides connecting said rests with said support, a guideway extending transversely to said divergent guides, cross heads movable in said guideway connected to said rests, a slide connected to said guideway, a plate adjustably connected to said slide, a follower carried by said 15 plate, and a cam coöperating with said follower for feeding said tools toward and from the work.

14. In a lathe, the combination of the bed frame, means for rotating the work, a carriage mounted for movement longitudinally 20 of the bed frame, slides mounted on said carriage, guide means for said slides, tool rests mounted on said slides, tools carried by said rests, a shaft journaled in bearings 25 on said carriage and movable therewith, cams on said shaft, followers for said cams operatively connected with said slides, said cams being formed to move said slides both toward and from the work, and means for 30 driving said shaft.

15. In a lathe, the combination with 35 means for supporting and rotating the work, of a carriage movable longitudinally of the lathe, a pair of rests for tools supported by the carriage and movable along divergent paths toward and from the work, tools carried by said rests, and means operable independent of the movement of said carriage to feed said rests simultaneously 40 along their divergent paths.

16. In a lathe, the combination with 45 means for supporting and rotating the work, of a carriage movable longitudinally of the

lathe, a support slidably mounted upon the carriage, a tool rest support slidably mounted upon the first-mentioned support, one of said supports movable axially of the work and the other support movable toward and from the axis of the work, and separate power-driven cams operably connected to 50 the respective supports to positively move each support back and forth along its slide-way.

17. In a lathe, the combination of means for rotating work, a carriage movable longitudinally of the lathe, tool-supporting slides mounted at the front and rear of the carriage and movable toward and from each other, a transverse shaft rotatably mounted upon the carriage and extending continuously from front to rear of the carriage, cams secured to the shaft adjacent each end thereof, followers coöperating with the cams to reciprocate said slides, means adjustably to connect the followers with the slides to 55 vary the distance of said slides relative to said cams, and power and hand-operated means to rotate said shaft in different positions of the carriage longitudinally of the lathe.

18. In a lathe, the combination with means for supporting and rotating the work, of a carriage movable longitudinally of the lathe, tool supporting slides mounted at the front and rear of the carriage and movable 60 toward and from each other, a tool carried by each slide, a transverse shaft rotatably mounted upon the carriage and extending continuously from front to rear of the carriage, cams secured to said shaft adjacent 65 each end thereof, said cams operably connected to the respective slides and constructed to feed said tools toward the work to cut a predetermined depth therein, and to cause said tools to dwell to finish the bottom of 70 the cut and then withdraw the tools from the work.

In testimony whereof I have signed my name to this specification.

WILLIAM F. GROENE.
